TOY ROBOT COSTUME

Robert H. Crowle, Mount Prospect, and William G. Crowle, Deerfield, Ill., assignors to General Box Company, Des Plaines, Ill., a corporation of Delaware

Filed Mar. 12, 1962, Ser. No. 69,187

Term of patent 14 years

(Cl. D3—17)

FIGURE 1 is a front perspective view of a toy robot costume showing our new design;

FIGURE 2 is a side elevational view of the side not shown in FIG. 1;

FIGURE 3 is a rear elevational view; and

FIGURE 4 is a top plan view.

The dominant feature of our design resides in the portions shown in full lines, and the broken line portions indicating a human figure in FIG. 1 are for illustrative purposes only. The shading of the sleeves is to show color contrast.

We claim:

The ornamental design for a toy robot costume, substantially as shown and described.
